UNITED STATES PATENT OFFICE.

FREDERICK R. BURCH, OF SEATTLE, WASHINGTON, ASSIGNOR TO LOUIS A. BURCH, OF SEATTLE, WASHINGTON.

WINDMILL.

Application filed March 12, 1925. Serial No. 14,894.

This invention relates to windmills or, more particularly, wind actuated motors.

The object of the present invention is to provide an apparatus of this character which will be of strong and durable construction, efficient in operation, and which may be regulated to meet various duties and requirements in use.

The invention, generally, consists in a rotary mast with two vertically spaced sets of arms radiating therefrom, the arms of one set being disposed in vertical planes with the respective arms of the other set, and vertically arranged wings, preferably canvas sails, carried by the complementary arms of both sets of arms.

Said wings are, moreover, arranged to swing about vertical axes, and are connected one with the other in a manner to mutually regulate their operation under various wind conditions.

The invention further consists in the provision of wing controlling devices which act automatically responsive to increasing wind pressures to govern the windmill accordingly.

The invention further consists in manually controlled means for regulating the action of the wing members to prevent the operation of the windmill under any wind velocity.

The invention still further consists in the novel construction, adaptation and arrangement of parts hereinafter described and claimed.

In the accompanying drawings,—

Figure 1 is a vertical section of apparatus embodying the invention in a construction now preferred by me, said section being taken substantially on broken lines 1—1 of Fig. 4. Fig. 2 is a fragmentary horizontal sectional view taken on broken line 2—2 of Fig. 1. Figs. 3 to 6, inclusive, are plan views, shown somewhat diagrammatically, illustrating relative positions of the sails in various operative and inoperative positions.

In said drawings, the reference numeral 10 represents a vertical shaft or mast which is shown as being reinforced by means of tie-rods 11 and struts 12.

The lower end of said mast is journaled in a foot bearing provided within a casing 9 which is desirably supported by means of gimbal devices 13, or an equivalent, above a foundation 14.

The upper end of the mast is journaled in a ring 15 which in the illustrated embodiment is connected as by means of guys 16 with suitable anchor posts or an equivalent, not shown, to maintain the mast substantially vertical. 60

Rigid with the mast are pairs of radiating arms 17 and 18, four pairs being shown. The complementary arms 17 and 18 of each pair thereof are arranged parallel, or nearly so, with each other and in the same vertical plane. 65

19 represent stays, connecting the outer ends of each pair of mast arms together, said arm ends being also connected by stays 20 and 21 with the mast as shown in Fig. 1. The stays 20 and 21 are each advantageously formed of two rods which are adjustably coupled with each other by turn buckles 22, or equivalent tensioning means. 70

Connected to each of the stays 19 is an upper boom 23 and a lower boom 24, the same being pivotally connected intermediate their length, as at 25 and 25¹ to the respective stay to provide at one side of the pivotal connections arms 23¹ and 24¹, and arms 23² and 24² at the other side. The outer ends of the arms 23¹ and 24¹ of each pair of arms are connected as by two-part tie-rod whose parts 27 are coupled as by 80 means of a turn buckle 28. 75

Located between the complementary booms are wings or sails designated by A, B, C, and D, the head and foot of each sail being secured to the respective boom arms 23² and 24²; the fore-leech of the sail being secured as by means of rings 31 to the associated stay 19. 80

The booms 23 are raised to spread the sails, and lowered to furl them, as by means of halyards 32 having an end of each connected to the respective boom and thence through blocks 33 depending from the mast arms 17, said halyards being led through suitable guides, such as indicated by 33¹, 90 provided upon the mast arms 18, the other ends 32¹ of the halyards being secured to cleats, as 34, or other attaching means provided upon the mast within convenient reach of an attendant. 100

The sail-carrying boom arms 23² and 24² have secured to their outer ends 35 and 35¹, ropes 36 and 37 which are rove through pulleys, such as 38, secured to the outer ends of the arms 23¹ and 24¹ of the booms pertaining 110

to the adjacent sails circumferentially of the windmill as represented in Figs. 3 and 4, for example. These ropes 36 and 37, two for each sail, lead through pulleys 39 and 40 upon the respective mast arms and thence extend as leads, such as 41 and 42, to a heavy body 46 to which the various ropes 36 and 37 are detachably connected as by hooks or other known means, not shown.

Supplemental to the ropes above described, I provide means for securing a sail or sails edgewise to the wind so that, when desired, the latter may be rendered incapable of revolving the sails. As illustrated, such sail securing means comprise ropes 47 and 48 which are secured to the outer ends 35 and 35¹ of the arms 23² and 24² of the booms of one sail, as A for instance, said securing ropes leading through guides or pulleys 44 provided upon the respective mast arms and are fastenable to means, such as a cleat 49, provided upon the mast.

The operation of the above described embodiment of the invention is as follows: Under ordinary working conditions and with a moderate wind blowing in the direction of the arrows W, and assuming that the sails A, B, C, and D, at one period of their revolution, denoted by direction arrow K, occupy the relative positions in which they are represented in Fig. 3, that is to say—with respect to the wind direction, sail D is at substantially right angles thereto, sail B is nearly so, and sails A and C are disposed in acute angular relations to the wind.

The reason the sails occupy these relative angular positions is because the effective wind pressures upon the various sails tend to turn them about their respective axes in the directions indicated by arrows a, b, c, and d; subject, however, to the regulating ropes which are controlled by the force of gravitation exercised by the heavy body 46 (Fig. 1). The turning of the sails about their individual axes is thus constrained by said regulating ropes which, for convenience of explanation, may be designated in the diagrammatic views 3 to 6 inclusive by a¹, b¹, c¹ and d¹. More particularly, with reference to Fig. 3, the sail D receiving the maximum force of the wind is held by means of both of the ropes d¹ and a¹ from turning about its axis d² and, in turn, reacts through rope a¹ of sail A to keep the latter in its illustrated rotary position about its axis a². Furthermore, the rope c¹ from the sail C serves to hold the sail B as shown in Fig. 3. The rope b¹ being at this time slack.

Assuming now the sails revolve into the positions in which they are illustrated in Fig. 4, the wind impelled turning movements of the sails with regard to their axes of rotation a², b², c² and d² will cause the ropes a¹, d¹, and c¹ to be taut and the rope b¹ to be slack.

In each of the sail positions above explained and, in fact, in practically all other positions which the sails assume when subjected to a wind of moderate force, each sail contributes to effect the orbital travel of all of the sails about the mast or the axis of the mast's rotation. When the wind velocity, however, increases the apparatus regulates itself to cause relatively higher velocity of winds to become impotent, so far as producing any injury to the apparatus.

This automatic sail regulating function will be understood with reference to Fig. 5, wherein a wind pressure greater than that by which the machine is intended to produce power, the sails A, B, C, and D will successively occupy the angular positions in which sails A and B are represented in Fig. 5, i. e.—edgewise positions or nearly so, to the wind, the other sails C and D meanwhile presenting sail surfaces to the wind insufficient to be harmful except in tempests or gales such as oftentimes occur in some districts.

In such automatic protective action, a material increase of air pressure upon the sails will serve to effect the elevation of the heavy body 46 (Fig. 1) which, it is to be noted, constitutes a gravity controlled governor. In the illustrated example (Fig. 5) the effective lengths between sails of the regulating ropes are extended, and each such rope becoming slack successively when in transit through the region in which the rope c¹ is shown.

For adjusting the apparatus to ensure a wind becoming ineffective to revolve the sails, and also for the purpose of withstanding gales, all that is requisite is that the attendant disengages from the heavy body 46 all of the regulating ropes a¹, b¹, c¹ and d¹ (such as denoted by 36 and 37 in Figs. 1 and 2) to permit the sails to swing like weather-vanes with respect to their axes; and in addition by securing the sail A in parallel relation to the mast arms 17 and 18 therefor, as accomplished by means of the ropes 47 and 48 and the cleat 49.

It is believed that the construction of the illustrated embodiment which is now preferred by me of the invention, its mode of operation, and the manner in which the same is regulated to meet working conditions or exigencies will be clear from the foregoing description.

I do not wish to be understood as confining myself specifically to the illustrated construction, as I may wish to avail myself of changes in design, proportions and otherwise which may come within the spirit of the invention as defined in the following claims.

What I claim, is,—

1. In a windmill, the combination with a rotatable mast having pairs of arms radiating therefrom, the arms of each pair

- thereof being located one above the other, of sails positioned between each pair of arms, said sails being arranged for rotary movements about axes concentric with the mast 5 and extending vertically through the respective arms and revolute with the latter, halyards depending from the upper of said arms for supporting the respective sails, said halyards also serving for raising and lowering the sail selectively into and out of operating positions, and means connecting the adjacent sails for mutually regulating the rotative actions thereof in their revolute travel about the mast axis. 10
- 15 2. In a windmill, in combination, a rotatable mast, arms rigid with said mast and radiating therefrom, sails provided with booms pivotally connected to the respective arms for rotative movement about substantially vertical axes, regulating ropes connecting the booms of the successive sails with each other circumferentially of the windmill, and governing means for controlling the action of the respective regulating ropes. 20
- 25 3. In a windmill, the combination with a rotatable mast and arms radiating therefrom, sails pivotally connected to said arms for rotative movement about substantially vertical axes, said sails being revolute in unison with said mast, regulating means connecting the successive sails with each other circumferentially of the windmill, and a gravity actuated governing means for controlling the action of the respective regulating 30 means. 35
4. In a windmill, a mast mounted for rotation, arms rigid with said mast and extending radially therefrom, said arms being disposed in pairs, a stay connecting each pair of arms, a sail mounted for rotary motion to each of said stays, means for elevating and lowering said sails into operative and inoperative positions, flexible means connecting the sails one with the other for regulating the angularity of their positions with respect to the wind, and means for securing one of the sails to the associated arms and in a predetermined position with respect thereto, and means for rendering the sail regulating means inoperative. 40
- 45 5. In a windmill arranged to have all of its sails exposed simultaneously to a wind, a rotatable mast, a series of rotatable sails arranged for revolute travel about the axis of the mast for driving the latter, and means connecting the successive sails with each other circumferentially of the windmill for regulating the angles of the planes of all of the sails with respect to the wind. 50
- 55 6. In a windmill, a mast having two sets of radiating arms disposed at two elevations, stays connecting the complementary arms of each set thereof, sails connected at their fore-leeches to the respective stays, a head boom and a foot boom for each sail, halyards connected to the upper booms for raising and lowering the respective sails, regulating ropes connecting the booms at the adjacent sails with each other, and gravitation controlled means connected to said regulating ropes to enable the latter to regulate the action of said sails responsive to variations in wind velocities. 60
- 65 7. In a windmill, a mast having two sets of radiating arms disposed at two elevations, stays connecting the complementary arms of each set thereof, sails connected at their fore-leeches to the respective stays, a head boom and a foot boom for each sail, halyards connected to the upper booms for raising and lowering the respective sails, regulating ropes connecting the booms at the adjacent sails with each other, and gravitation controlled means connected to said regulating ropes to enable the latter to regulate the action of said sails responsive to variations in wind velocities. 70
- 75 8. In a windmill, a mast having two sets of radiating arms disposed at two elevations, stays connecting the complementary arms of each set thereof, sails connected at their fore-leeches to the respective stays, a head boom and a foot boom for each sail, halyards connected to the upper booms for raising and lowering the respective sails, regulating ropes connecting the booms of the adjacent sails with each other, gravitation controlled means connected to said regulating ropes to enable the latter to regulate the action of said sails responsive to variations in wind velocities, and means for securing one of said sails in a direction substantially radially of the mast. 80
- 85 9. In a windmill, a rotary mast, two sets of arms radiating therefrom in vertically spaced-apart relation, stays connecting the outer ends of complementary arms of both sets thereof, stays extending from said arm ends to the mast, a pair of booms pivotally connected intermediate their lengths to each of the first named stays to provide boom arms at opposite side of the same, a sail between each pair of booms, the head and foot thereof being connected to correspondingly directed arms of the respective pair of booms, and sail regulating means connecting the sail carrying arms of each boom with the other arms of an adjacent pair of booms. 90
- 100 10. In a windmill, in combination, a rotatable mast, sails revolute with the mast and rotatable about the axes of the respective sails, of direction regulating means for said sails, said means comprising flexible devices connecting the sails one with the other in series circumferentially of the windmill, and governing means responsive to changes in the velocity of the wind for controlling said regulating means. 105
